UNITED STATES PATENT OFFICE

145,689

DESIGN FOR A KITCHEN TOOL OR SIMILAR ARTICLE

Allen J. Eggleston, Chicago, Ill., assignor to Ekco Products Company, a corporation of Illinois

Application June 30, 1945, Serial No. 120,414

Term of patent 14 years

(Cl. D44—29)

To all whom it may concern:

Be it known that I, Allen J. Eggleston, a citizen of the United States, residing at Chicago, in the county of Cook and State of Illinois, have invented a new, original, and ornamental Design for a Kitchen Tool or Similar Article, of which the following is a specification, reference being had to the accompanying drawing, forming part thereof.

Fig. 1 is a front perspective view of the kitchen tool or similar article, showing my new design.

Fig. 2 is a side elevational view of the same.

Fig. 3 is a front elevational view thereof, when turned through an angle of 90 degrees relative to the position shown in Fig. 2.

The dominant feature of the design resides in the portion shown in full lines.

I claim:

The ornamental design for a kitchen tool or similar article, as shown and described.

ALLEN J. EGGLESTON.
